United States Patent Office

Des. 179,250

Patented Nov. 20, 1956

179,250

GLOVE

Julius A. Higier, Johnstown, N. Y.

Application June 19, 1956, Serial No. 41,963

Term of patent 7 years

(Cl. D3—11)

Fig. 1 is a plan view of the back of a glove showing my new design; and

Fig. 2 is a plan view of the palm side of the same.

I claim:

The ornamental design for a glove, substantially as shown.
